GAME BOARD

Richard L. Vannatter, R.R. 1, Middletown, Ind.

Filed July 15, 1965, Ser. No. 86,169

Term of patent 14 years

(Cl. D34—5)

The figure is a plan view of a game board showing my new design.

The game board is of conventional thickness. The dominant features of my design reside in the portions shown in full lines.

I claim:

The ornamental design for a game board, substantially as shown and described.
